James Varley

United States Patent Office.

JAMES VARLEY, OF HUDSON, ASSIGNOR TO HIMSELF AND D. M. SMYTH,
OF ORANGE, NEW JERSEY.

Letters Patent No. 98,129, dated December 21, 1869.

IMPROVEMENT IN NECKTIE AND COLLAR COMBINED.

The Schedule referred to in these Letters Patent and making part of the same.

To all whom it may concern:

Be it known that I, JAMES VARLEY, of the city and county of Hudson, and State of New Jersey, have invented a new and useful Improvement in Imitation Neckties for Shirt-Collars; and I do hereby declare that the following is a full and exact description thereof, reference being had to the accompanying drawings, and to the letters of reference marked thereon, making a part of this specification.

I make use of a paper necktie, cut out in the proper shape, and attached at one end to the band of a paper collar by an eyelet.

This mode of attachment allows the necktie to be turned down out of the way in buttoning on the collar to the shirt, and also holds the tie properly to place when it is turned up beneath the opposite side of the collar.

I cut out the necktie from paper, or similar material, in the shape represented in

Figure B, which represents the imitation tie attached to the collar.

Figure C represents it adjusted to enable the wearer to button the collar upon the shirt-band.

To enable others skilled in art to make and use my invention, I will describe its construction and operation.

They are cut with a knife, of suitable shape, from a continuous sheet or sheets of paper, or other suitable material, and may be swaged in dies of proper form to produce the raised imitation of knot in the centre; also, to represent stitching or embroidery.

They are then made fast to that part of the collar as represented in Fig. B, with a metallic eyelet, upon which they may be turned or adjusted for convenience of buttoning the collar on the neck-band, when the imitation tie may be turned back into the fold of the collar, so as to represent a neat tie.

I do not claim a necktie cut out of paper, or similar material; but

What I claim, and desire to secure by Letters Patent, is—

Uniting one end of the necktie to the band of the collar by an eyelet, so that said necktie may be turned down for allowing the collar to be buttoned or held up in place by said eyelet, when turned up beneath the collar, as set forth.

JAMES VARLEY.
